METHOD OF FORMING CONTAINERS

Swan Smith, White Bear, Minn., assignor to David C. Shepard, St. Paul, Minn.

Application December 5, 1935, Serial No. 53,022

8 Claims. (Cl. 93—39.1)

My invention relates to containers and to the method of forming the same and has for an object to provide a method by which paper containers can be constructed economically and expeditiously.

Another object of the invention resides in providing a method of constructing conical containers in which sheets of paper arcuate in form are cut from a roll or length of paper by single arcuate cuts extending transversely of the paper and of the same degree of curvature and of a curvature such that when the sheets are wound one upon the other and secured together, the edges of the sheets at one end of the container register with one another.

An object of the invention resides in providing a method of constructing containers in which the sheets after assembly are simultaneously trimmed at the other end of the container.

A still further object of the invention resides in providing a method of constructing containers in which the curvature of the sheets is such that the edges of the sheets at the lower end of the container register with one another.

Another object of the invention resides in providing a method of constructing containers in which a flanged bottom is inserted into the wall structure of the container with the lower edge of the flange in register with the lower edge of the wall structure, and in which a metal hoop U-shaped in cross section is applied to the flange and wall structure and attached thereto.

A still further object of the invention resides in providing a method of constructing containers in which a hoop having an inwardly turned flange is applied to the upper end of the container with said flange in engagement with the free edge of the container formed by the trimming of the same.

Other objects of the invention reside in the detailed steps of the invention and in the performance thereof as hereinafter illustrated and/or described.

In the drawings:

Fig. 1 is a perspective view of a container constructed in accordance with the invention.

Fig. 2 is a perspective view showing the method of winding the sheets of paper upon one another.

Fig. 3 is a perspective view of the bottom of the container.

Fig. 4 is a developed view of a length of paper from which the blanks used in forming the container are cut.

Fig. 5 is a fragmentary sectional view taken on line 5—5 of Fig. 1 and drawn to a larger scale.

Fig. 6 is a perspective view showing the method of applying the bottom hoop to the container.

Fig. 7 is a perspective view showing the method of trimming the wall structure of the container.

A container constructed by my improved method is illustrated in Figs. 1 and 6 and is indicated in its entirety by the reference character A. This container comprises a body 10 open at the top which includes a wall structure 11 and a bottom 12 attached thereto by means of a hoop 13. A hoop 14 protects and reinforces the upper end of the container. Any suitable cover may be used to close the top of the container and the same not being involved in the method of the invention has not been shown in the drawings. The various parts of the body of the container will now be described in detail.

The bottom 12 may be constructed of paper or any other suitable material. When constructed of paper a number of sheets of paper are employed which are circular in form and which are of a diameter somewhat greater than the diameter of the container at the lower end thereof. These sheets are glued one to the other and before the glue has set are placed in suitable dies and pressed to form a planiform portion 15 adapted to extend across the bottom of the container and a flange 16 depending from the planiform portion thereof as clearly shown in Figs. 3 and 5 and adapted to lie against the inner surface of the container. This bottom is then dried either in the atmosphere or in an oven to cause the glue to set, or, if preferred, heat may be applied to the dies so that the bottom is caused to take the desired form when removed from the dies. When so constructed the flange 16 extends outwardly from the planiform portion 15 at right angles thereto.

For building up the wall structure 11 of the container individual sheets of paper 19 are employed which are cut transversely from a roll of paper, the unrolled portion of which is indicated at 30. The sheets 19 are of a length equal to the width of the paper 30 and the ends 31 and 32 of these sheets are formed by the lateral edges of the paper coming from the roll and are parallel to each other. The sheets 19 are severed from the roll by means of a pair of cutters traveling in an arc of a circle. Each sheet is severed by the same cutters traveling over the same path so that the upper edges 26 of the sheets have the same curvature as the 55

lower edges 25. The radius of the arc of movement of the cutters is such that when the sheets are wound or rolled upon a suitable mandrel, the lower edges 25 of the sheets register with one another to form a true circle at the lowermost portion of the container. Due to the fact that the container is in the shape of a frustum of a cone a true circle at the top could only be produced by cutting the sheets along a line indicated in Fig. 5 by the reference numeral 45. However, the sheets are not individually cut along this line and when assembled the edges 26 thereof are out of register and form overlying crescent-shaped bands 44 at the upper portion of the container.

The method of assembling the sheets 19 is as follows: A mandrel diagrammatically indicated at 17 in Fig. 2 is employed which is in the shape of a frustum of a cone of dimensions corresponding to the inner dimensions of the wall structure of the container. The diameter of this mandrel at its smaller end is equal to the inner diameter of the wall structure 11 at the lower end thereof. One of the sheets 19 which is cut as previously described and which is designated at 19a is wrapped about the mandrel with the lower edge 25 thereof in register with the edge of mandrel 17 at the smaller end thereof. The upper surface of the sheet at the first applied end 28 thereof is coated with glue or other adhesive. As the sheet is applied to the mandrel the other end 29 of the sheet is caused to overlie the end 28 and adheres thereto forming a joint indicated in its entirety by the reference numeral 39. Due to the particular shape of the sheet the overlap has the form of a trapezoid increasing in width throughout the length of the container and being greatest at the lower end of the container.

After the first sheet has been applied, other sheets are applied which are exactly of the same size and shape as the first sheet. One of these sheets is indicated at 19b and is shown as partly wrapped about the mandrel and the previously applied sheet. The succeeding sheets are arranged with their edges 25 in register with one another and with the corresponding edge of the first sheet and are progressively wrapped about the mandrel so that the joints 39 become equally distributed about the periphery of the wall structure 11 with a portion of one joint overlapping a portion of the adjacent joint. As each sheet is applied, the same is coated with glue or other adhesive and caused to adhere to the previously applied sheets. Enough sheets are applied to give the body structure the desired thickness and strength. Five to six sheets are usually used. Due to the fact that the curvature of the edge 25 is such that said edge forms a true circle when the sheets 19 are applied, all of said edges lie in register with one another and form the lowermost edge 20 of the wall structure 11 of the container.

The hoop 13 is constructed from a straight narrow strip of sheet metal which is folded longitudinally along a medial line to form a straight structure, U-shaped in cross section, having outer and inner walls 22 and 23 and a connecting portion 24. This straight structure so formed is run through crimping rolls which engage the inner wall 23 and crimp the same to form corrugations 27 in said wall. By means of this method of construction, the length of the wall 23 is reduced as compared to the length of the wall 22 and the formerly straight structure is converted into circular form with the walls 22

and 23 substantially cylindrical. After crimping, the ends of the walls are secured together as by riveting, soldering or welding to form a hoop of the desired circumferential dimensions.

After the wall structure 11 has become cured 5 the bottom 12 is attached thereto. This is accomplished as follows: Hoop 13 is first set on a horizontal surface with the portion 24 resting upon said surface. The wall structure is next set into the space between the walls 22 and 23 of said hoop. The hoop is of such dimensions that the upper end of wall 22 snugly fits against the outer surface of wall structure 11 when the said wall structure is in proper position, which positively centers the hoop with respect to the 15 wall structure. This leaves a space between the inner surface of wall structure 11 and the wall 23 of hoop 13 of uniform width which is wider than the thickness of the flange 16 of bottom 12. Bottom 12 is next inserted into the wall structure 11 with the flange 16 lowermost and is forced downwardly by means of a plunger applied to the planiform portion 15 thereof. The outer diameter of flange 16 is slightly greater than the 20 internal diameter of the wall structure 11 at the locality thereof in proximity to the portion 41 of the bottom, measured prior to the application of the bottom to the wall structure. This causes the lowermost marginal portion of the flange 16 to hug the inner surface of wall structure 11 as 30 the bottom is being forced in position. Flange 16 hence positively clears the upper end of wall 23 of hoop 13 as the bottom descends. Due to the shape of flange 16 and wall structure 11, said flange is urged into tight contact with wall structure 11 as the bottom is forced into position. After the bottom is in place, a scoring roll 42 is applied to the outer wall 22 and a punching roll 43 applied to the inner wall 23 of the hoop 35 which are diagrammatically indicated in Fig. 6. 40 These rolls are brought toward one another and as the bottom structure of the container passes between said rolls, the outer wall 22 is formed with inwardly extending beads 35, 36 and 37. At the same time the inner wall 23 is formed with 45 a plurality of barbs 33 which extend towards the beads 35 and 36. Due to the fact that the body of the container is constructed of paper, beads 35, 36 and 37 and the barbs 33 become imbedded in the wall structure 11 and flange 16 and the 50 said hoop is rigidly secured thereto. At the same time a rib 38 is formed on said wall structure opposite the bead 35 which extends into the interior of the container. The bead 35 is so disposed that the rib 38 fills in the space 40 formed 55 by the rounded corner 41 of the bottom 12 which serves as a fillet and also assists in holding the parts attached to one another. It will be noted that the hoop 13 in addition to holding the parts attached to one another and restraining relative movement thereof, forms a guard 60 which protects the lowermost edges 20 and 21 of the flange 16 and the lowermost marginal portion 18 of the container proper. The rim or base 24 of the hoop 13 serves as a support for the 65 container proper, and also functions as a skid by means of which the container may be readily slid on the surface on which it rests.

Due to the fact that the curvature of the upper edge 26 of the sheets 19 is the same as that of the 70 lower edges 25, the said edges do not form a true circle nor do they register with one another but leave crescent shaped bands 44 which are distributed about the upper periphery of the container. If the sheets 19 were cut along a line 75

indicated in Fig. 4 the upper edges of the sheets would also form a true circle. However, the sheets are not individually cut along such lines but after the body structure 11 is completed the entire body structure embodying all of the sheets 19 is trimmed by means of shearing discs 46 and 47 (diagrammatically indicated in Fig. 7) along a circumferential line including the corners 48 of the sheets 19, which line coincides with the lines 45. This removes the crescent shaped bands 44, leaving the body structure of the container with an exposed smooth circular upper edge 49. The trimming of the wall structure of the container may be accomplished either after or before the bottom is applied thereto.

The exposed edge 49 of the wall structure 11 of the container is protected by the hoop 14 which also serves to reinforce the open end of the container. This hoop is conical or tapered the same as the wall structure 11 and is constructed from a sheet of metal bent into the desired form and having the ends thereof riveted or welded together. The lowermost edge of said hoop 14 is beaded, as at 51, around a reinforcing ring 53. This reinforcing ring is constructed of wire and the ends thereof are butt welded together. In applying the hoop 14 to the container, said hoop is passed over the bottom of the container and along the tapered wall structure 11 into its fitted position thereon with the upper margin of the hoop projecting beyond the upper edge 49 of the wall structure. This portion of the hoop is then turned over to form an inwardly extending lip 54 overlying said edge 49 of the wall structure 11. This lip serves to protect the said edge and at the same time serves to retain the hoop in its fitted position on said wall structure. In addition to the lip 54, rivets 55 may be used to further secure the hoop 14 to the wall structure 11, which rivets 30 extend through said hoop and wall structure and are riveted in place as shown in Fig. 5.

By the use of the method disclosed a minimum number of operations is required. The severing of the sheets from the roll by single transverse cuts 45 simplifies the formation of the sheets. By making the curvature of the lower edges of the sheets such that said edges form a true circle when built into the body structure of the container, any slight irregularities arising in the assembly of the sheets will be covered up when the metal hoop is applied to the container. By trimming the upper end of the wall structure all of the excess material is advantageously removed at one time and a clean smooth edge is provided against which the lip of the upper hoop may abut. My improved method involves a minimum amount of waste and labor and makes for the economical manufacture of conical paper containers in a highly practical manner.

Changes in the steps of the method herein disclosed may be made within the scope of what is claimed without departing from the spirit of the invention.

Having described my improved method what I claim as new and desire to protect by Letters Patent is:

1. The method of forming the side wall structure of a conical container from a length of paper, which consists in cutting the paper transversely along curved lines to form separate sheets having the same degree of curvature at the top and bottom, and of a curvature such that the edges of the sheets at one end of the formed wall structure will register with one another, in securing the sheets together, in wrapped relation, one

upon the other with the registrable edges in register, and in trimming the several sheets of the formed wall structure collectively at the other end of the said wall structure.

2. The method of forming the side wall structure of a conical container from a length of paper which consists in severing separate sheets from the length of paper, each sheet being formed by a single transverse cut along a curved line of a degree of curvature such that the edges of the sheets at one end of the formed wall structure will register with one another, in securing the sheets together in wrapper relation, one upon the other, with said registrable edges in register, and in trimming the several sheets of the formed wall structure collectively at the other end of said wall structure.

3. The method of forming the side wall structure of a conical container from a length of paper which consists in severing separate sheets from the length of paper, each sheet being formed by a single transverse cut along a curved line of a degree of curvature such that the edges of the sheets at the lower end of the formed wall structure will register with one another, in securing the sheets together in wrapped relation, one upon the other, with said registrable edges in register, and in trimming the several sheets of the formed wall structure collectively at the upper end of said wall structure.

4. The method of forming the side wall structure of a conical container from a length of paper which consists in severing separate sheets from the length of paper, each sheet being formed by a single transverse cut along a curved line of a degree of curvature such that the edges of the sheets at the lower end of the formed wall structure will register with one another, in securing the sheets together in wrapped relation, one upon the other, with said registrable edges in register, inserting the lower end of the side wall structure into a metal hoop, U-shaped in cross section, of a diameter providing an annular space between the inner surface of the wall structure and the inner wall of the hoop, in inserting into the wall structure a bottom with a depending cylindrical flange of an external diameter greater than the least internal diameter of the wall structure, in forcing the bottom downwardly to cause the free edge of the flange to follow along the inner surface of the wall structure and into said annular space, and in clinching the inner and outer walls of the hoop against the flange and lowermost marginal portion of the wall structure, respectively.

5. The method of forming conical containers which consists in inserting the smaller open end of a conical side wall structure into a metal hoop, U-shaped in cross section, of a diameter providing an annular space between the inner surface of the wall structure and the inner wall of the hoop, in inserting into the wall structure a bottom with a depending cylindrical flange of an external diameter greater than the least internal diameter of the wall structure, in forcing the bottom downwardly to cause the free edge of the flange to follow along the inner surface of the wall structure and into said annular space, and in clinching the inner and outer walls of the hoop against the flange and lowermost marginal portion of the wall structure, respectively.

6. The method of forming containers which consists in inserting the open end of a tubular side wall structure into a hoop U-shaped in cross section and having a perimeter such as to pro-

vide an annular space between the inner surface of the wall structure and the inner wall of the hoop, in inserting into the wall structure a bottom with a depending flange adapted to fit snugly in the lowermost marginal portion of the wall structure, in forcing the bottom downwardly to cause the free edge of the flange to follow along the inner surface of the wall structure and into said annular space, and in clinching the inner and outer walls of the hoop against the flange and lowermost marginal portion of the wall structure, respectively.

7. The method of forming containers having a tubular side wall member and a flanged bottom member provided with juxtaposed marginal portions secured together by means of a U-shaped hoop, said method consisting in inserting the marginal portion of one of said members into said hoop and in centering said hoop with reference thereto to provide an annular space within said hoop, adjacent one of the surfaces of the marginal portion of the inserted member, for the reception of the marginal portion of the other member, in sliding said other member along said inserted member with the marginal portion thereof engaging said surface of said inserted member and guiding said marginal portion of the second

named member into said annular space by means of said surface and in clinching said hoop upon the juxtaposed marginal portions of said members.

8. The method of forming conical containers which consists in inserting the smaller end of an open ended conical side wall structure into a metal hoop, U-shaped in cross section, of a diameter providing an annular space between the inner surface of the wall structure and the inner wall of the hoop, in inserting into the wall structure from the other end a bottom with an outwardly extending cylindrical flange of an external diameter greater than the least internal diameter of the wall structure, in forcing the bottom inwardly into the wall structure to cause the free edge of the flange to follow along the inner surface of the wall structure to stretch the wall structure and force the same toward the outer wall of the hoop and to increase said annular space, whereby said flange is readily received within said space as said flange follows along the inner surface of the wall structure and in clinching the inner and outer walls of the hoop against the flange and lowermost marginal portion of the wall structure, respectively.
